ONE-HAND CABLE CUTTER

Harry M. Webster, Malden, Mass., assignor to H. K. Porter, Inc., Somerville, Mass., a corporation of Massachusetts

Application September 19, 1958, Serial No. 762,044

1 Claim. (Cl. 30—254)

This invention relates to a portable cable cutter for one-hand operation. The invention provides a novel construction enabling efficient use of the cutter under the exacting demands arising in connection with the use of helicopters, although the field of use of the tool is not limited thereto.

Men are lowered away from and retrieved to a hovering helicopter by means of a small but strong metal cable and goods are similarly transported. Under emergency conditions it may be necessary to cut the line. It is contemplated that the passenger or the man on the ground on the one hand, and the man tending the line at the helicopter on the other, will each have a cutter as will be described. Its construction admits his applying the cutter to the line quickly and surely, even under adverse conditions, and perhaps at the outermost distance he can reach while holding on with the other hand and quickly cutting it by a single stroke.

The invention will be well understood by reference to the following description of the illustrative embodiment thereof shown by way of example in the annexed drawings, wherein:

Fig. 1 is a side elevation of the tool in open position;
Fig. 2 is a side elevation illustrating the closed position;

Fig. 3 is an edge view of the head portion thereof in the closed position; and

Figs. 4-7 are enlarged sections on the correspondingly numbered lines of Fig. 1.

In the interest of simplicity, strength and rapidity of action the tool herein disclosed is of the simple crossed lever type having a single pivot 10 engaging two crossing levers defining at one side of the pivot the head levers 12 and 14, and at the other side the two handle levers 16 and 18. The crossing levers are herein shown as of conventional built-up construction, the head levers having tails which extend past the pivot and engage the proximal portions of the handles, themselves mounted on the pivot, to operate as units therewith. The head levers move past one another in the manner of shear blades although, as will appear, they are not sharpened throughout their length.

In the following description I shall use the terms "right" and "left" to refer to the construction as viewed in Fig. 1, the words however being merely relative, and I shall use the words "distal" and "proximal" with relation to the pivot 10, "proximal" being that portion of the part being referred to which is nearer the pivot and "distal" the portion further away.

A one-hand tool is characteristically operated by a squeezing action of the hand exerting pressure between the curved over fingers, one handle resting against the middle phalanges and the butt of the palm adjacent the proximal ends of the metacarpals where the other handle rests. A cable of the kind referred to can be severed by a one-handed tool of suitable strength and quality so operated. However, to secure an adequate mechanical advantage, the opening between the head levers would be small, which might not be objectionable if we could

2

position the tool on stationary work or when holding the work with the other hand, conditions which may not obtain in practice.

According to the invention therefore, the proportion of the handles in general more resembles a two-handed tool of the type found in some pruners. Thus, by way of example, in the tool illustrated in the drawing, the straight line distance between the pivot 10 and the end of the handles was nine inches. A spring 20 tends to open the handles 16 and 18 to an extreme position beyond the compass of the partly closed grasping hand. The head levers 12 and 14 cut close to the pivot 10 and, when the handles are in the fully open position they are so located as to permit them to be quickly applied to the work to engage the same and guide it to the point of cut, while the handles are so constructed that, when the tool is in the open position with the handles widely spread, it may be supported on the palmar side of the outstretched hand and retained by the tips of a finger and the thumb and, when so supported, guided to the work and, after preliminary engagement is effected, partly closed (against the action of the spring 20 only, no cutting being done) by a slight movement of that finger and thumb effective to shift the handles into a position suitable for grasping by the hand as a whole to effect the cut.

I shall describe the head levers 12 and 14. The head lever 12 is relatively long and has a bent-over pointed extremity from which extends a broad-faced surface 22, concaved toward the other lever and leading to a stop surface 24 adjacent the pivot 10. Just outwardly of this stop surface the blade has a recess 26 of a width slightly exceeding the diameter of the cable (taken in the example as $5\frac{1}{2}$ of an inch) and somewhat deeper, so that the cable may pass therein beyond the extension of the line 22. The distal wall of the recess may be relieved at its end as shown at 27 to provide a wider entrance to facilitate the passage of the cable into the recess. The bottom portion of the recess 26 is beveled to a cutting edge in the plane between the two levers, as shown at 28. The opposite head lever 14 is considerably shorter than the lever 12 and has a convexly curved broad-faced surface 30 opposing the concavely curved surface 22 of head lever 12. The proximal portion of this head lever 14 opposite the recess 26 is beveled (on the further side viewing Fig. 1) at 32, the edges 28 and 32 providing a shearing cut when the two head levers move across one another.

I shall now describe the preferred form of handles here disclosed. The right-hand handle 18 has a nib 34 extending outwardly from its outer side which in the closed position of the tool receives the sinus where the thumb joins the body of the hand, the distal portion 36 of the handle being adapted for engagement with the butt of the palm in the final cutting movement. The left-hand handle 16 is provided on its outward side with a loop 38 which receives the index finger while the opposing distal extension 40 of the handle beneath the loop receives the other fingers during the cutting action proper.

In the open position the widely spaced levers may be supported resting on the extended hand, but held against loss by the bent-over end of the index finger in the loop 38 and the tip of the thumb bearing on the distal side of the nib 34. The tool may be easily shaken loose and dropped if necessary when the hand is in this position. The single loop will not catch and hold. In this open position of the parts with the tool balanced on the hand, it may be steered even at arms length and the outwardly projecting end of head lever 12 "hooked" against one side of the cable and the tool thrust forward in a plane transverse to the cable. The opposed shorter lever 14 does not stand in the way. The word "hooked" has been enclosed with quotation marks because the end 22 of

head lever 12 does not make a hook engagement with the work which could take charge and perhaps snatch the tool from the hand. As the cable follows down along the concave surface 22 it will be guided on the other side by the convex surface 30 of the shorter lever. Any wobbling will cause it to bounce back and forth between these two surfaces and work its way down into the gradually narrowing space between surfaces 22 and 30 toward the pivot 10 until it reaches the position of the recess 26, and can move into the same. This action will be felt and as opportunity offers crooking of the forefinger and a corresponding sliding movement of the thumb under the nib 34 will partially close the jaws and drop the handles into the partially closed hand, ready to be completely closed by the powerful grasping action of the closing hand, with resultant severance of the cable by the edges 28 and 32.

Suitable means are provided for holding the tool closed against the spring 26 when not in use, conveniently arranged adjacent the hand and adapted to be very quickly released by motion of a finger. Herein a short length of bead chain 42 is secured to one handle and carries a ring 44 to engage over a pin 46 on the other. Simplicity is the desideratum particularly as the users may be wearing gloves. The end of one handle has a hole 48 to receive a lanyard.

I claim:

A one-hand cutter for wire cables or the like comprising a simple pair of crossed levers secured by a pivot,

the proximal ends of the levers defining a pair of handles and the distal ends a pair of head levers the opposed sides of which move over one another in closing in the manner of shear blades, means being provided for normally urging said pairs to the open positions, the handles being long and spreading when open beyond the normal gripping scope of a hand, the handles having projections positioned for cooperation with a finger and thumb of the outspread hand so that the tool may be thereby supported and partially closed to bring the handles within said scope, one of the head levers being relatively long and tapered to a point with a concave curve on the inner side from said point to adjacent the pivot, there being a stop surface transverse to said curve at the rearward end of one of said levers, said side having just outward of said stop surface a deep notch to receive a cable and encompass at least half the circumference thereof, the inner portion of the notch being beveled to a cutting edge in the plane between the head levers, the other and shorter head lever being convexly curved on its inner side, the aforesaid curved sides of the two levers being, in the open position, spaced from each other in the region distal to the stop surface and defining an area between them narrowing as the center pivot is approached, said other lever having a portion of its inner side which in closing moves across the notch beveled to a cutting edge in the plane between the head levers.
